UNITED STATES PATENT OFFICE.

AUGUST H. KATTERJOHN, OF DENVER, COLORADO, ASSIGNOR TO THE DENVER FOCK DRILL MANUFACTURING COMPANY, OF DENVER, COLORADO, A CORPORATION OF DELAWARE.

FLUID-OPERATED MOTOR.

Application filed January 18, 1923. Serial No. 613,482.

The present invention relates to automatic distributing valves for motors operated by expansive fluid under pressure, and is in the nature of an improvement on the valve structure disclosed in the patent to Waugh, No. 919,270, April 20, 1909.

One of the primary objects is to provide a relatively large supply of fluid that is initially admitted to the piston chamber behind the piston at the very beginning of its working stroke, the arrangement being such that the valve has a short movement and consequent quick action.

The preferred form of construction is illustrated in the accompanying drawings, wherein:

Figure 1 is a longitudinal sectional view through a motor of the hammer piston type equipped with the valve mechanism, and showing the piston in a position to start on its working stroke.

Figure 2 is a view similar to Figure 1, but illustrating the relation of the parts when said working stroke is completed.

Figure 3 is a cross sectional view on the line 3—3 of Figure 2.

Figure 4 is an end view of the distributing valve,

Figure 5 is a side elevation of the same.

In the embodiment disclosed, a cylinder member 6 is provided with the usual piston chamber 7, in which operates a reciprocating piston designated 8. A valve chest 9 is fitted to the rear end of the cylinder member 6, and is preferably provided with an extension 10 that fits therewith, forming a rear wall for the piston chamber 7. This valve chest is provided with a valve chamber designated generally by the reference numeral 11, said valve chamber having its front end opening into the rear end of the piston chamber 7 through a circular series of ports 12 that open into an annular groove 13 formed in the front end of the valve chest around the valve chamber 11.

A rear head 14 for the tool abuts against the rear end of the valve chest 9. This head may be in sections, as shown, and the inner section is provided with a central plug extension element 15 having a reduced annular portion 16 and terminating at its inner end in a head 17 that closes the front end of the valve chamber, and has a plurality of slots

18 milled in its rear end. The rear head 14 is provided with the usual connection for a supply hose, and has a throttle valve 19 controlling the supply of motive fluid to a passageway 20 formed in said rear end 14, in one side of the valve chest 9, and in the rear end of the cylinder member 6. This passageway is in communication with a port 21 opening into a relatively large groove 22 formed in the rear end of the cylinder member around the valve chest extension 10, and providing a reservoir of considerable capacity for motive fluid. This reservoir has communication through ports 23 with an internal groove 24 formed in the valve chest around the valve chamber 11 and constituting in effect a part of the reservoir 22.

A reciprocating automatic distributing valve 25 is located in the valve chamber 11 and surrounds the plug extension 15, being spaced from the reduced portion 16 of said plug extension and slidably fitting on the relatively long head 17, as illustrated in Figure 2. The front end of this valve is provided with a series of ports 26 that afford communication between the groove or reservoir 22—24 and the space between the valve and the reduced portion 16 of the plug extension, this space forming an internal reservoir 27 within the valve. It is to be noted that the ports 26 are at all times in communication with the groove 24 and reservoir 27, whether the valve is in its rearmost position, as shown in Figure 1, or in its foremost position as shown in Figure 2, so that fluid under pressure supplied through the passageway 20 will always have access to both the reservoirs 22 and 27.

The valve chest 9 is provided in the rear of the groove 24 with spaced grooves 28 and 29 located on opposite sides of an intermediate groove 30. The groove 30 has an exhaust port 31 shown diagrammatically in Figures 1 and 2 that opens to atmosphere. The exterior face of the valve 25 is provided with cut-away portions 32 that afford communication between the groove 24 and groove 28, when the valve is in its foremost position and between the groove 28 and the exhaust groove 30 when the valve is in its rearmost position. From the groove 28 a passageway 33 leads to the front end of the piston chamber 7 in advance of the piston

when the latter is at the front end of its forward stroke. The groove 29 is in communication with a passageway 34 that opens into the rear portion of the piston chamber 7 a short distance in advance of its rear end. The cylinder member moreover has a central exhaust port 35 opening from the piston chamber 7 to atmosphere, and a passageway 36 leading from the piston chamber 7 between the front end of the passageway 34 and the exhaust port 35, opens into a chamber 37 at the rear end of the valve chest. In this chamber operates an external flange 38 formed upon the rear end of the valve 25. From the rear portion of the chamber 37 extends an exhaust port 39 that opens to atmosphere, and is shown diagrammatically in Figures 1 and 2. This port is of smaller cross sectional area than the passageway 36. Another relief port 40, shown diagrammatically in Figures 1 and 2 opens from the front end of the chamber 37 to atmosphere. It will be noted that the internal bore of the tubular valve 25 is of two diameters, providing an annular shoulder 41, forming a pressure surface against which motive fluid in the reservoir 27 acts to move the distributing valve 25 forwardly.

Assuming the parts in the positions illustrated in Figure 1, the piston 8 is at the rear end of its stroke and is in position to move forwardly on its working stroke. When so related it will be noted that the valve 25 is in its rearmost position. Consequently air or other motive fluid can pass from the reservoir grooves 22 and 24 around the head 17 of the plug extension and through the ports 12 into the rear end of the piston chamber to drive said piston forwardly. At the same time motive fluid in the internal reservoir 27 can also flow freely around the plug extension head 17 and through said ports 12 into the rear end of the piston chamber. Consequently a relatively large body of air acts upon the piston to initiate its forward movement. As it moves forwardly, exhaust in advance of the same will take place through the port 35 and also through the passageway 33, groove 28, cut-away portions 32 of the valve, groove 30 and exhaust port 31. The valve is held in its rearmost position during the forward movement of the piston by the air acting on the front end of said valve. When the piston uncovers the passageway 36, motive fluid behind the piston will pass through said passageway 36 and enter the chamber 37 behind the flange 38. While some of this fluid will escape through the exhaust port 39 the area of said port is so much smaller than the passageway 36 that pressure will build up in the chamber 37, and acting against the relatively large rear face of the flange 38, will, together with the pressure against the internal shoulder 41,

move the valve forwardly. This cuts off the supply of motive fluid around the plug head 17, as illustrated in Figure 2 and causes the groove 28 to be brought into communication with the groove 24 through the cut-away portions 32 on the exterior of the valve. As a consequence live fluid will flow through the passageway 33 to the front end of the cylinder, driving the piston rearwardly. The exhaust will now take place through the port 35, which has been passed by the piston and through the passageway 34, the groove 29 around the valve to the groove 30, and out of the exhaust port 31. This action will continue until the passageway 36 is closed by the returning piston, whereupon any pressure in the chamber 37 and against the flange 38 of the valve due to the exhausting fluid will be entirely relieved by the open exhaust 39. When the inner end of the passageway 34 is passed by the piston the fluid behind said piston will be trapped and pressure built up which will operate against the front end of the valve sufficiently to overcome the pressure against the internal shoulder 41, thereby moving the valve rearwardly, or to the position shown in Figure 1.

In these operations, it is to be noted that the valve has a very short movement and when in its foremost position a relatively small amount of air or other motive fluid is utilized through the passageway 33 to drive the piston rearwardly. Full pressure is therefore built up in the relatively large chambers or reservoirs 22-24 and 27, so that as soon as the valve shifts to the rear and opens the valve chamber to the rear end of the piston chamber, a larger body of compressed motive fluid flows immediately into the piston chamber and initiates the working stroke of the piston.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new and desire to secure by Letters Patent, is:

1. In a fluid operated motor, the combination with a cylinder member having a piston chamber and a piston operating in the chamber, of an automatic hollow distributing valve located in rear of the piston chamber and having a front open end, a fluid reservoir within the valve having means of communication at its front end with the rear end of the piston chamber, and means for automatically operating the valve to cause

its front end to move to and from a position across said means of communication to periodically cut it off.

2. In a fluid operated motor, the combination with a cylinder member having a piston chamber and a piston operating in the chamber, of a valve casing in rear of the piston chamber and having an annular groove in its front end and ports opening 10 from the groove into the rear end of the piston chamber, a movable automatic hollow distributing valve in the valve chamber having an open front end, a fluid reservoir within the valve having communication at 15 its front end with the groove, the front end of said valve being movable with said valve to and from a position between the reservoir and the groove, and means for effecting the automatic operation of the valve.

20 3. In a fluid operated motor, the combination with a cylinder member and a piston operating therein, of a valve chamber, a plug element in the valve chamber, and a hollow distributing valve surrounding the 25 plug element and having a portion surrounding and spaced therefrom forming a fluid reservoir within the valve, said chamber having communication through the front end of the valve with the cylinder 30 member and the front ends of said distributing valve and plug element cooperating to control such communication.

4. In a fluid operated motor, the combination with a cylinder member and a piston 35 operating therein, of a valve chamber, a plug element in the valve chamber, a hollow distributing valve surrounding the plug element and having a portion spaced therefrom forming a fluid reservoir within the 40 valve, said chamber having communication around the plug element with the cylinder member and said distributing valve and plug element cooperating to control such communication, a motor fluid supply passageway, 45 and means affording constant communication between the fluid supply passageway and the reservoir.

5. In a fluid operated motor, the combination with a cylinder member and a piston 50 operating therein, of a valve chamber, a plug element in the valve chamber, a hollow distributing valve surrounding the plug element and having a portion spaced therefrom forming a fluid reservoir within the 55 valve, said chamber having communication at one end around the plug element with the cylinder member and said distributing valve having one end cooperating with the plug element to control such communication, and 60 a motor fluid supply passageway, said valve having a port affording constant communication between the fluid supply passageway and the reservoir.

6. In a fluid operated motor, the combination with a cylinder member having a pis-

ton chamber, and a piston therein, of a valve chamber opening into the rear end of the piston chamber, a plug extension in the valve chamber having a reduced portion forming a fluid reservoir and a head at the 70 inner end of said reservoir, a valve in the valve chamber surrounding the plug extension, said valve having an open end slidably fitting the head and said valve having a portion spaced from the reduced portion, 75 said end of the valve cooperating with the plug to cut off communication between the reservoir and the piston chamber when in one position and admit motive fluid from the reservoir through its front end into the 80 rear end of the piston chamber when in a different position, and means for supplying motive fluid to the reservoir.

7. In a fluid operated motor, the combination with a cylinder member having a piston chamber and a piston therein, of a valve chamber opening into the rear end of the piston chamber, a plug extension in the valve chamber having a reduced portion forming a fluid reservoir and a head at the 85 inner end of said reservoir, a valve in the valve chamber surrounding the plug extension and having an open front end slidably fitting the head, said valve being spaced from the reduced portion, the front end of 90 said valve and the plug head controlling communication between the reservoir and the piston chamber, and a motive fluid supply passageway opening through one side of the valve chamber, said valve having a port 95 in constant communication with the supply passageway and the reservoir.

8. In a fluid operated motor, the combination with a cylinder member having a piston chamber and a piston therein, of a valve 100 chamber opening into the rear end of the piston chamber, a plug extension in the valve chamber having a reduced portion forming a fluid reservoir and a head at the inner end of said reservoir, a valve in the 105 valve chamber surrounding the plug extension and having an open front end slidably fitting both the head of the plug element and the wall of the valve chamber to cut off communication between the reservoir and the 110 piston chamber when in one position and open communication through its front end into the rear end of the piston chamber when in a different position, and means for supplying motive fluid to the reservoir and 115 effecting the operation of the valve.

9. In a fluid operated motor, the combination with a cylinder member having a piston chamber and a piston operating therein, of a valve chest having a valve chamber, a distributing valve in the valve chamber, motive fluid reservoirs both within and without the valve having separate outlet ports that are in communication with the piston chamber, and means for constantly 125

supplying motive fluid to both reservoirs, said valve controlling the passage of motive fluid from both reservoirs to the piston chamber.

- 5 10. In a fluid operated motor, the combination with a cylinder member having a piston chamber and a piston operating therein, of a valve chest having a valve chamber opening at one end into the piston chamber, a distributing valve in the valve chamber, motive fluid reservoirs both within and without the valve having separate outlet ports that are in communication with the piston chamber, and means for constantly supplying motive fluid to both reservoirs, said valve controlling the passage of motive fluid from both reservoirs through the open end of the valve chamber into the piston chamber.
- 15 20. 11. In a fluid operated motor, the combination with a cylinder member having a piston chamber, and a piston operating therein, of a valve chest having a valve chamber, a plug element extending into the valve chamber and having a reduced portion forming a motive fluid reservoir, a motive fluid reservoir outside the valve chamber having separate outlet ports that are in communication with the piston chamber, means
- 25 30. for constantly supplying motive fluid to both reservoirs, a tubular valve surrounding the plug element and interposed between the reservoirs, said valve controlling communication between the reservoirs and the piston chamber, means for supplying motive fluid under pressure to the reservoirs, and means controlled by the piston for actuating the valve.
- 35 40. 12. In a fluid operated motor, the combination with a cylinder member having a piston chamber, and a piston operating therein, of a valve chest having a valve chamber opening at one end into the piston chamber, a plug element extending into the valve chamber and having a reduced portion forming a motive fluid reservoir, a motive fluid reservoir outside the valve chamber, said reservoirs having common means of communication from their corresponding ends with the piston chamber and said means of communication being outside both reservoirs, a tubular valve surrounding the plug element and interposed between the reservoirs, said valve when in one position closing the open end of the valve chamber and controlling communication between the reservoirs and the piston chamber, means for supplying motive fluid under pressure to both reservoirs, and means controlled by the piston for actuating the valve.
- 45 50. 55. 60.

13. In a fluid operated motor the combination with a cylinder member and a piston operating therein, of an automatic hollow distributing valve having an open end, a fluid reservoir within the valve having com-

munication with the cylinder member, said communication being controlled by said end of the valve, means for constantly supplying motive fluid to the reservoir, said valve having an internal pressure surface 70 adjacent the open end and operated on by motive fluid supplied to the reservoir, and means controlled by the piston for overcoming the said pressure and shifting the valve in opposition thereto.

75 14. In a fluid operated motor, the combination with a cylinder member having a piston chamber and a piston therein, of a valve chamber opening into the rear end of the piston chamber, a plug extension in the valve chamber having a reduced portion forming a fluid reservoir and a head at the inner end of said reservoir, a valve in the valve chamber surrounding the plug extension, said valve having one end slidably fitting the head and being spaced from the reduced portion, said valve controlling communication between the reservoir and the piston chamber, means for constantly supplying motive fluid to the reservoir, said slidably fitted end of the valve having an internal pressure surface operated on by motive fluid supplied to the reservoir, and acting to move the valve to a position to cut off said communication, and means controlled by the piston to periodically operate the valve against said pressure on the internal surface to open said communication.

80 85. 90. 95. 100. 105. 110. 115. 120. 125.

15. In a fluid operated motor, the combination with a cylinder member having a piston chamber and a piston operating therein, of a valve chest having a valve chamber opening into the rear end of the piston chamber, a forwardly extending plug extension in the valve chamber having a head at its free end and a reduced portion forming a motive fluid reservoir, a second reservoir around the valve chamber, having communication with the piston chamber independent of the front reservoir, and in communication therewith, a reciprocatory valve in the valve chamber surrounding the plug extension and having an open front end slidably mounted on the head and coacting therewith to close the communication between said valve chamber and piston chamber and close the two reservoirs from the latter, said valve having a port affording constant communication between the two reservoirs, and means for constantly supplying motive fluid to both of said reservoirs.

130. 135. 140.

16. In a fluid operated motor, the combination with a cylinder member having a piston chamber and a piston operating therein, of a valve chest in line with and in rear of the piston chamber and having a valve chamber opening at its front end into the rear end of the piston chamber, a forwardly extending plug extension in the

- valve chamber having a head at its free end and a reduced portion forming a motive fluid reservoir opening through the valve chamber into the piston chamber, a second reservoir around the valve chamber and in communication through the front end of the same with the piston chamber, a reciprocatory valve in the valve chamber surrounding the plug extension and having an open front end slidable on the head and cooperating therewith to close the communication between said valve chamber and piston chamber and thereby close the two reservoirs from the latter, said valve having a port affording constant communication between the two reservoirs, means for supplying motive fluid to one of said reservoirs, the interior of said valve at the open end having a pressure surface acted on by the motive fluid in the inner chamber to shift said valve to said closing position, and means controlled by the piston to overcome said pressure and shift said valve in the opposite direction.
17. In a fluid operated motor, the combination with a cylinder member having a piston chamber and a piston operating therein, of a valve chest in rear of the piston chamber and having an open ended valve chamber, a plug member extending through the valve chamber and having a reduced portion forming a reservoir, and a head at its inner end, said valve chest having a reservoir surrounding the valve chamber, and a reciprocatory open ended valve in the valve chamber operating between the two reservoirs and having a port affording constant communication between them, said reservoirs having a common outlet in direct communication with both and opening into the rear end of the piston chamber and the end of the valve being movable into and out of said outlet to cut both reservoirs simultaneously off from the piston chamber.
18. In a fluid operated motor, the combination with a cylinder member having a piston chamber and a piston operating therein, of a valve chest in rear of the piston chamber and having an open ended valve chamber, a plug member extending through the valve chamber and having a reduced portion forming a reservoir and a head at its inner end, said valve chest having a reservoir surrounding the valve chamber, and a reciprocatory open ended valve in the valve chamber operating between the two reservoirs and having a port affording constant communication between them, said reservoirs having a common outlet in direct communication with both and opening into the rear end of the piston chamber and the end of the valve being movable into and out of said outlet to cut both reservoirs simultaneously off from the piston chamber.

In testimony whereof, I affix my signature.

AUGUST H. KATTERJOHN.
